Attest

UNITED STATES PATENT OFFICE

GUSTAV JOHNSON, OF WEST ROXBURY, MASSACHUSETTS, ASSIGNOR TO UNITED-CARR FASTENER CORPORATION, OF CAMBRIDGE, MASSACHUSETTS, A CORPORATION OF MASSACHUSETTS

SEPARABLE FASTENER

Application filed December 10, 1930. Serial No. 501,272.

My invention aims to provide improvements in separable fastener members of the hook and eye type.

In the drawing which illustrates a preferred embodiment of my invention:

5 Figure 1 is a cross-section through an installation embodying my invention;

Fig. 2 is a rear view of the hook member installation;

10 Fig. 3 is an elevation of the hook-presenting plate; and

Fig. 4 is an elevation view of the "eye" member of the fastener.

Referring to the particular embodiment of 15 my invention selected for illustration by the drawing, I have shown a separable fastening means of the hook and eye type used as a "three-side lock" fastener installation. In

20 Figure 1 I have shown the "eye" member 1 secured to a support 2, which may be the body of a motor vehicle, and a "hook" member 3 attached to a flexible carrying medium 4, which may be a side curtain to be secured to the body of the motor vehicle. The "eye" 25 member is attached by means of screws 5 and the "hook" member is attached by means of an attaching plate 6 having prongs 7 passing through the carrying medium 4 and through slots 8 in the "hook" member 3 and bent 30 against the plate portion thereof.

My improved "hook" member is formed from a single piece of sheet metal, a portion of the center of which is pressed out to form a hook 9 curved in transverse cross-section 35 to strengthen it. The "hook" member 3 is also provided with an integral spring finger 10 which extends from the edge of the plate portion (Fig. 3) toward the center at the opposite side of the plate portion from that side at which the hook 9 is located and underlies the hook 9, as best shown in Fig. 1. Both the hook 9 and the spring finger 10 are angled with relation to the plate portion of the member 3 and are spaced from each other.

45 The "eye" member is formed from sheet metal and has a hook-engaging portion 11 pressed from the center portion thereof and bent into the form of a loop outstanding from the plate portion, as shown in Figure 1. The hook-engaging portion 11 is rolled from the

metal taken from the center of the plate portion of the member 1 to provide a circular cross-section.

To attach the "hook" member 3 to the "eye" member 1, it is merely necessary to pull downwardly on the curtain 4 and slide the hook 9 under the hook-engaging portion 11, so that the hook-engaging portion is received between the hook 9 and the spring finger 10, as shown in Figure 1. The spring finger prevents rattle of the fastener members and holds the parts against accidental separation. When the fastener members are engaged they cannot be separated by outward or lateral stresses, except by a pull exerted upon the lower edge of the curtain to pull the hook 9 out of engagement with the hook-engaging portion 11. Thus, I have provided a simple, inexpensive and durable so-called three-side lock fastener because of the fact that the members cannot be separated except by a pull at a predetermined side thereof.

While I have shown and described a preferred embodiment of my invention, I do not wish to be limited thereby, because the scope of my invention is best defined in the following claims.

I claim:

1. A separable fastening installation comprising, in combination, a supporting structure, a fastener member located at one side of said supporting structure, an attaching member located at the other side of the supporting structure, attaching means extending from one of said members through the supporting structure and engaged with the other member to secure the parts of the installation together, a hook member formed from the material of said fastener member within the periphery thereof and extending at an angle to the general plane of the fastener member and a spring finger forming a part of the fastener member and extending generally parallel to and in spaced relation from the hook member thereby to cooperate with the hook member to receive and hold an eye presented by a cooperating fastener member.

2. A separable fastening member comprising 100 a plate member having a hook portion

formed from the material of said plate member within the periphery thereof and standing away from the plane of said plate member, said hook portion forming an aperture in said plate member, a spring finger formed integral with said plate member and extending from one edge of said plate member toward said aperture, said spring finger being located at the opposite side of the plate member from that side at which the hook portion is located and having a portion thereof extending through the aperture for cooperation with the hook portion and having its end terminating adjacent to that end of the hook where it joins the plate member.

In testimony whereof, I have signed my name to this specification.

GUSTAV JOHNSON.
